UNITED STATES PATENT OFFICE.

HUGH J. MURPHY AND EDWARD F. MURPHY, OF TROY, NEW YORK.

TROLLEY-MOUNT.

1,392,846.

Specification of Letters Patent.

Patented Oct. 4, 1921.

Application filed February 23, 1921. Serial No. 447,085.

To all whom it may concern:

Be it known that we, HUGH J. MURPHY and EDWARD F. MURPHY, citizens of the United States, residing at Troy, in the 5 county of Rensselaer and State of New York, have invented new and useful Improvements in Trolley-Mounts, of which the following is a specification.

Reference may be had to the accompanying drawings and the reference characters marked thereon, which form a part of this specification. Similar characters refer to similar parts in the several figures therein.

The principal object of the invention is 15 to prevent injury to the cross-wires and other overhead structure of a trolley railway due to the jumping of the trolley from the trolley-wire.

Specific objects of the invention will appear in connection with the following description.

In carrying out our invention we provide means whereby a trolley which has jumped from the trolley-wire is at once automatically 25 swung down to, and maintained at a level sufficiently below that of the trolley-wire to prevent the trolley from engaging the overhead structure such as cross-wires and the like.

Figure 1 of the drawings is a view in side elevation of our improved trolley-mount showing the trolley-pole in retrieved position in which the trolley is supported at a level below that of the trolley-wire, the 35 trolley and trolley-wire being not shown.

Fig. 2 is a top plan view of the same.

Fig. 3 is a view similar to Fig. 1, showing the trolley-pole in position for the trolley to engage the trolley-wire, the trolley and 40 trolley-wire being not shown.

Referring to the drawings wherein the invention is shown in preferred form, 1 is a trolley-pole-support in the form of a turn-table rotatively mounted upon a post 2, on 45 the roof, 3, of a trolley-car.

The trolley-pole, 4, has a base, 5, pivotally mounted at 6, upon the support, 1, whereby the pole can be swung back and forth between a substantially vertical position and a substantially horizontal position.

The trolley-pole-base, 5, is provided with a slot, 7, which extends substantially at right angles to the axis of the pole which slot terminates at its inner end in a seat, 8, and at its outer end in a seat, 9, said seats 55 being severally adapted to receive a pin, 10, adapted to travel along the slot from seat to seat.

A pin, 10, is connected by a plurality of coil-springs, 11, with the support, 1, to exert a pull upon the pin which tends to more or less raise the trolley-pole when the pin is located in either of the seats, 8 and 9.

The force of the spring, 11, is so regulated that when the pin, 10, occupies the inner seat, 8, the pull upon the trolley-pole is sufficient to hold it at substantially the angle shown in solid lines in Fig. 3, at which angle the trolley is adapted to engage and be held upwardly against the trolley-wire. 70

The angle of the slot, 7, is such that when the trolley-pole is elevated to substantially vertical position, as indicated by the dotted lines in Fig. 3, as when the trolley jumps from the trolley-wire, the pin, 10, automatically shifts from the inner seat, 8, to the outer seat, 9, passing over the intervening abutment, 12, in the slot, 7.

The form and arrangement of the slots and seats are such that when the pin, 10, occupies the outer seat, 9, the pull of the spring, 11, is not sufficient to raise the trolley-wire to the angle shown by solid lines in Fig. 3, but is only sufficient to raise the pole to substantially the angle shown 85 in Fig. 1, in which position the trolley is maintained at a level below that of the trolley-wire, in which position the trolley passes safely beneath the overhead structure, such as cross-wires, etc.

When it is desired to restore the trolley to operative engagement with the trolley-wire it becomes necessary to shift the pin, 10, from the outer seat, 9, back to the inner seat, 8, and we have shown means for thus shifting the pin by movement of the trolley-pole down to substantially horizontal position as indicated by dotted lines in Fig. 1.

The pin-shifting mechanism comprises a curved lever, 13, pivoted at 14, upon the 100

trolley-pole base, 5, and so shaped that when it is swung upwardly it tends to force the pin, 10, out of the outer seat, 9, and inwardly along the slot, 7, into the inner seat, 8.

This upward swinging movement of the lever, 13, is caused by engagement with a fulcrum block, 15, on the support, 1, as the trolley-pole is swung down to approximately horizontal position.

The position which the lever thus assumes in forcing the pin, 10, into the inner seat seat, 8, is indicated by dotted lines in connection with the dotted position of the trolley-pole in Fig. 1.

A stop-pin, 16, is adjustably mounted in a slot, 17, in the trolley-pole base in position to form a stop or support for the lever, 13, in the more elevated positions of the trolley-pole.

The operation of the device is as follows: Normally the parts are in the position shown by solid lines in Fig. 3, in which position the trolley would be in engagement 25 with the trolley-wire, and the pin, 10, seated in the inner seat, 8. As the trolley jumps from the wire the pull of the spring, 11, causes the pole to be suddenly elevated to approximately vertical position as indicated 30 by dotted lines in Fig. 3, in which position the pull of the spring causes the pin, 10, to shift from the inner seat, 8, along the slot, 7, to the outer seat, 9.

As the pole rebounds, the pull of the 35 spring, 11, is not sufficient to hold it at its normal angle, but is sufficient to support it in a somewhat lower position, as shown in Fig. 1, in which position the trolley is below the level of the trolley-wire and the 40 overhead structure.

The pole is mounted in this safe position, as shown by solid lines in Fig. 1, until the operator is ready to restore the trolley to the wire, and in doing this, he has merely 45 to pull the trolley-pole down to substantially horizontal position, as indicated by dotted lines in Fig. 1, thereby causing the lever, 13, to shift the pin, 10, from the outer seat to the inner seat, restoring to the spring 50 its normal pole-supporting force so that as the operator permits the trolley to rise to the wire, it will be held up against the wire upon engagement therewith.

What we claim as new and desire to secure 55 by Letters Patent is—

1. In a device of the class described and in combination, a trolley-pole-support; a trolley-pole-base pivotally mounted upon said support and provided with a slot approximately at right angles to the axis of the trolley-pole, said slot being formed with two seats at different distances from the pivot of the trolley-pole-base; a pin movable along said slot and seatable in the re-

spective seats; and a trolley-pole-supporting 65 spring-connection between said pin and said support, acting with less force when the pin is seated in the outer, than when the pin is seated in the inner, of said seats, said pin being automatically shifted from the inner 70 to the outer seat when the trolley-pole is in approximately vertical position.

2. In a device of the class described and in combination, a trolley-pole-support; a trolley-pole-base pivotally mounted upon 75 said support and provided with a slot approximately at right angles to the axis of the trolley-pole, said slot being formed with two seats at different distances from the pivot of the trolley-pole-base; a pin movable along said slot and seatable in the respective seats; a trolley-pole-supporting spring-connection between said pin and said support, acting with less force when the pin is seated in the outer, than when the pin is seated in the inner, of said seats, said pin being automatically shifted from the inner to the outer seat when the trolley-pole is in approximately vertical position; and a movable pin-engaging member automatically engageable with said pin to force the pin from the outer to the inner of said seats when the trolley-pole is in approximately horizontal position.

3. In a device of the class described and 95 in combination, a trolley-pole-support; a trolley-pole-base pivotally mounted upon said support and provided with a slot 100 formed with two seats at different distances from the pivot of the trolley-pole-base, separated by an abutment; a pin movable along said slot and seatable in the respective seats; a spring-connection between said pin and said support, acting with less force when the pin is seated in the outer, than when it is seated in the inner, of said seats, said pin being automatically shiftable over said abutment from the inner to the outer of said seats when the trolley-pole is in approximately vertical position; and means actuated by movement of the trolley-pole to 105 approximately horizontal position for shifting said pin over said abutment from the outer to the inner of said seats.

4. In a device of the class described and 115 in combination, a trolley-pole-support; a trolley-pole-base pivotally mounted upon said support and provided with a slot approximately at right angles to the axis of the trolley-pole, said slot being formed with 120 two seats at different distances from the pivot of the trolley-pole-base; a pin movable along said slot and seatable in the respective seats; a trolley-pole-supporting spring-connection between said pin and said support, acting with less force when the pin is seated in the outer, than when the pin is seated in the inner, of said seats, said pin

being automatically shiftable by the spring force alone from the inner to the outer of said seats when the trolley-pole is in approximately vertical position; a fulcrum-block on said support; and a pin-shifting lever pivoted upon the trolley-pole-base engageable with said fulcrum-block to shift the pin from the outer to the inner of said

seats when the trolley-pole is brought to approximately horizontal position.

In testimony whereof we have hereunto set our hands this 19th day of February, 1921.

HUGH J. MURPHY.
EDWARD F. MURPHY.
